Attorneys—Kenneth L. Miller and Robert A. Green

ABSTRACT: The disclosure is of a gas plasma cell having electrode carrying end walls of a material having a high dielectric constant, greater than that of glass, so that the cell has high capacitance. The disclosure is also of a matrix of such cells and combinations of such cells and other cells having lower capacitance.

GAS-FILLED DISPLAY DEVICE HAVING CAPACITIVE ENVELOPE

BACKGROUND OF THE INVENTION

The present invention relates to a gas plasma cell made of glass and containing a gas which is adapted to glow when a operating potential is applied between electrodes on the end walls of the cell. The cell has the characteristic that, when glow is produced, electrical charges are generated and stored on the end walls of the cell, and the glow can be sustained by the application of sustaining potential which may be smaller than the firing potential. Known gas plasma cells normally have small capacitance, and this characteristic imposes certain limitations on the operation and utility of the cells.

SUMMARY OF THE INVENTION

Briefly, the invention relates to a gas plasma cell which is of such configuration that it has high capacitance which permits the cell to generate a detectable current when it is fired and glows. Among other things, due to the high capacitance, the cell produces brighter light output than cells of the prior art. A plurality of cells embodying the invention can also be combined in a matrix for performing and displaying electrical logic functions.

BRIEF DESCRIPTION OF THE DRAWING

In the drawing:

FIG. 1 is a sectional elevational view of a light-producing cell embodying the invention and a circuit in which it may be operated;

FIG. 2 is a sectional elevational view of a portion of a modification of the invention;

FIG. 3 is a sectional elevational view of a modification of the invention;

FIG. 4 is a sectional elevational view of a modification of the device of FIG. 3;

FIG. 5 is a perspective view of a device embodying the invention and schematic representation of a circuit in which it may be operated;

FIG. 6 is a sectional elevational view of a modification of the invention and a schematic representation of a circuit in which it may be operated; and

FIG. 7 is a sectional elevational view of a modification of the invention and schematic representation of a circuit in which it may be operated.

DESCRIPTION OF THE PREFERRED EMBODIMENTS

Apparatus 10 embodying the invention comprises a cell formed of insulating material such as glass and including a hollow cylindrical envelope 20 having end walls 30 and 40 which form a gastight seal therewith. According to the invention, discs or plates 50 and 60 of a material having a relatively high dielectric constant, called K, are secured to the end walls 30 and 40, respectively, and electrodes 70 and 80, respectively, are secured in turn to the discs 50 and 60. The discs 50 and 60 increase the capacitance of the cell to a favorably high level, and they may be of any suitable material, for example, a ceramic such as barium titanate. The discs may also be of any convenient thickness. It is clear, of course, that glass walls 30 and 40 may be omitted and discs 50 and 60 can themselves comprise end walls to cell 10, as shown in part FIG. 2. Glass typically has a dielectric constant of $7\epsilon_0$, and plates 50 and 60 preferably are in the range of about 400 to about 2,000 ϵ_0 .

The cell 10 includes an ionizable gas which can be fired and caused to flow and maintain the glow when a suitable sustaining voltage is applied to it. Suitable gases are argon, neon, krypton, nitrogen, helium, etc., or mixtures of these gases. Mixtures of neon and nitrogen are effective, and a mixture of 93 per cent neon and 7 percent nitrogen is particularly suitable. The gas may be introduced into the cell in any well-known fashion.

A typical circuit for operating cell 10 includes, in series, a source 100 of sustaining potential, a source 110 of firing pulses, and an impedance, for example, a resistor 120 connected between contacts 70 and 80. Output terminals 130 are provided on resistor 120. Operating parameters are determined generally by the size of the cell, the gas content, and the like, and for a cell having a thickness of a few mils and with a neon-nitrogen gas mixture, the sustaining potential produced by source 100 is an alternating signal of about 700 volts and a frequency of about 500 kc., and the firing signal produced by source 110 is a pulse of about ± 100 volts.

In one mode of operation of the cell 10, a sustaining signal is applied between electrodes 70 and 80 from source 100, and at a selected time a firing pulse from source 110 is also applied.

15 This combination of voltages causes the gas within the cell to ionize and glow, and the glow can be sustained by the sustaining potential. Due to the relatively high capacitance of the cell, when the cell fires, a usable current pulse can be detected in resistor 120. The cell may also be operated by first applying a firing pulse of sufficient amplitude and then sustaining the glow by the application of the sustaining potential.

20 Due to the relatively high capacitance of the cell, the cell exhibits a more intense or brighter glow at a selected operating frequency than would have been exhibited by cells of the prior art at the same frequency.

25 In a modification of the invention shown in FIG. 3, a display panel 150 is provided which includes a plurality of cells 10 of the type described above. In this case, it may be desirable to have the regions or bodies 50 and 60 of high dielectric material of one cell mechanically isolated from those of adjacent cells, as shown, to maintain electrical isolation between cells. It may be desirable for bodies 50 and 60 to have a larger diameter than the gas-filled volume of the cell as shown in 30 FIG. 1, for example. The panel 150 may be made in relatively simple fashion by assembling a sandwich of glass plates including an apertured central plate 160 and top and bottom glass plates 170 and 180. The individual bodies of high dielectric material 50 and 60 are secured to the top and bottom glass plates in vertical alignment with apertures in the central plate, and the individual contacts 70 and 80 are secured to the bodies 50 and 60. Separate electrical connections including output resistors 120 may be made to each cell through contacts 70 and 80 each cell, and each cell may be 35 operated individually to record intelligence and to display a light pattern.

40 In an alternative construction, shown in FIG. 4, the end walls of the cells themselves comprise the bodies 50 and 60 of high K material without an intervening plain glass layer being provided. This type of cell may also be made in the manner described above, with plates 170 and 180 being apertured and bodies 50 and 60 comprising inserts, or it may be made by embedding individual glass cells having bodies 50 and 60 as end walls in a suitable support medium of a synthetic resinous material.

45 Electrical connections may also be made as shown in FIG. 5. Assuming that the cells in panel 150 are arrayed in rows and columns, a single row lead 200 may be connected to each row of contacts 70 on the top surface, and a single column lead 206 may be connected to each column of contacts 80 on the bottom surface. An output impedance 120 is also provided for each cell in either its row or column conductor. As is well known with matrix-type devices such as this, an input signal applied to one row lead 200 and one column lead 206 will cause one cell to glow where the leads cross. Thus, the panel 50 150 as shown in FIG. 5 can be used to record intelligence in many different ways. For example, if a cell is on and is being sustained and has a firing signal applied to it, it will not change state and no current pulse will be detected in the associated resistor 120. Or, if a cell has sustaining signal applied to it but is not on, a firing pulse is applied and it turns on, then a detectable signal can be derived from the associated resistor 120. Operations of this type can be used in electronic logic 55 systems to process information. Systems and methods for

using the panel 150 in logic operations will occur readily to those skilled in the art.

Another unique embodiment of the invention is shown in FIG. 6 and comprises a cell pair including a first cell 210 having an envelope and end walls of low K glass, known as a low K cell, which is coupled to a second cell 220 of the type described above and known as a high K cell which has end walls 221 and 222 of material having high dielectric constant. In the simplest arrangement, one cell of each type is provided and both cells are formed in a single glass panel in operative relation with each other. Operative relation means that the cells are close enough to each other so that, when one generates ultraviolet light, the light can penetrate to and affect the operation of the other. Cell 210 has end electrodes 223 and 224, and cell 220 has end electrodes 225 and 226.

In one mode of operation of the cell pair, both cells 210 and 220 have sustaining potential applied to them from sources 227 and 228, respectively, and the low K cell 210 is fired by the application of a firing pulse from source 229. The firing of cell 210 generates ultraviolet light which is coupled to cell 220 through the glass between them. This radiation generates photoelectrons in cell 220 which, acting in the applied electric field, causes cell 220 to fire and generate a visual output and an electrical output in resistor 120. The cell pair in this case may be considered to be an amplifier.

The reverse operating sequence may be employed with cell

220 turning on cell 210 by means of ultraviolet light. Or in still another mode of operation (FIG. 7), the high K cell 220 may be coupled through its output impedance 120 by leads 230 to one or more low K cells 210, and the relatively large electrical output of the cell 220, when it is fired, can be used to fire the low K cells 210.

Of course, it is clear that the required synchronization between the various signals and the ultraviolet light is provided. In addition, different numbers of the two types of cells may be provided as required by a particular application.

I claim:

1. A display panel including a gas-filled cell having low capacitance and a gas-filled cell having high capacitance, circuit means coupled to each cell for firing the cell, said cells being coupled in close relationship so that the firing of one facilitates the firing of the other

2. The panel defined in claim 1 wherein said cells are positioned close together so that ultraviolet light generated by one when it fires can be transmitted to the other to facilitate its firing.

3. The cell defined in claim 1 and including an output impedance in the circuit of said high capacitance cell and leads coupling said output impedance across said low capacitance cell.
